UNITED STATES PATENT OFFICE

LUCIAN E. PARKER, OF WADSWORTH, OHIO, ASSIGNOR TO THE OHIO MATCH COMPANY,
OF WADSWORTH, OHIO, A CORPORATION OF OHIO

BOX

Application filed August 29, 1927. Serial No. 216,104.

In the vending of small articles, such as book matches and small boxes of matches, by means of vending machines, it is customary to fill the hoppers of such vending machines by 5 taking the articles from the original packages or containers in which they are packed and placing them in order in such hoppers.

This is a tedious and time-consuming operation, and in the case of book matches, unless the books are properly and carefully arranged in the hoppers of the machines, they will not feed therefrom properly when the machine is operated.

It is the object of the present invention to 15 provide an original package or container for book matches and other commodities that are put up as units and put on sale as such, said container having holes in its bottom, at either or both ends, for cooperation with the eject- 20 or mechanism of a vending machine, by which the contents of the container may be discharged, the holes being of any desired shape, such as circular or rectangular, and extending transversely of the bottom of the 25 box, and being wholly cut out or of the knockout variety.

The invention consists of a box, that is to say, an original package or container, adapted to receive goods in salable units, such as 30 book matches, such boxes being primarily provided for use in vending machines, the bottom of the box, at one or both ends, being provided with holes or openings to receive the ejectors of the vending machine for dis- 35 charging from the box and vending machine the units in sequence as they come before the ejectors, as I will proceed now more fully to explain and finally claim.

Describing the present invention as it re- 40 lates to the packing and dispensing of book matches, without thereby limiting its adaptability, it is to be noted that under the prevailing practice, book matches are packed in nested arrangement edgewise in paper boxes 45 having closed ends, sides and bottoms, and removable covers, but in my invention the vending machine is designed to receive in its hopper a complete box, that is to say, an original package of this type with the books 50 of matches therein, but with the cover or lid

removed, the books being ejected from the hopper and the box therein by appropriate mechanical ejecting mechanism.

In my application for patent for Vending machines, filed June 23, 1927, Serial No. 55 200,935, I have shown one form of boxes or containers, and a vending machine in which these boxes are used. In the present case, I show similar boxes and also modifications thereof. 60

In the accompanying drawings illustrating the invention, in the several figures of which like parts are similarly designated, Figure 1 is a perspective view of a complete original package of book matches, a part of the lid or cover thereof being broken away to show the arrangement of the match books therein. Fig. 2 is a perspective view, looking at the bottom of the box, and showing the bottom provided with ejecting holes at both ends, 65 the holes being entirely cut through. Fig. 3 is a fragmentary perspective view, looking at the bottom of the box, and with the holes of knockout or partially severed construction. Fig. 4 is a perspective view, looking 70 at the inside of the bottom of a box, in which the openings are slots. Fig. 5 is a perspective view, looking at the inside of the bottom of the box, in which the holes are of 75 the knockout or partially excised variety, of 80 slot form.

I have shown the invention as embodied in a box in which the sales units are packed in two columns or rows, and the openings in the bottom of the body of the box are arranged 85 opposite these columns, so that the lowermost two of the stacks or rows of sales units may be ejected simultaneously, but I do not limit my invention to such a box, or to the number of rows of sales units therein. 90

The box may be of pasteboard, cardboard or other paper fabric, or material, and composed of a body 1, a removable lid or cover 2, a bottom 3. The bottom 3 of the body is provided with holes 4, of any suitable shape to 95 receive the ejecting mechanism of a vending machine and permit it to contact with the contents of the box and eject the same. As already indicated, the body of the box is inserted as an original package in the machine 100

with the cover removed and with the open end of the box facing the discharge portion of the machine, and the bottom of the box facing the ejecting mechanism, so that as the 5 ejecting mechanism is moved into contact with the box, it will enter the holes and eject the contents, unit by unit, successively. Where the units are arranged in the box in stacks or parallel rows, there will be an equal 10 number of pairs of holes 4. These pairs of holes may be arranged at opposite ends of the box so that the box may be put in the machine either end down.

Instead of entirely cutting out the holes, as 15 shown in Fig. 2, these holes may be merely incised or partly severed, on the knockout principle, as indicated at 5, Fig. 3, the movement of the ejectors serving to knock out the parts.

20 Instead of having round holes to correspond with round ejectors, I may use rectangular holes, at either or both ends of the box, as indicated at 6, in Fig. 4, for cooperation with similar ejectors in the vending machine. These rectangular holes may be cut 25 out, as shown in Fig. 4, or they may be of the incised or partly severed or knockout type, as shown at 7, in Fig. 5.

Other variations in the details of construction 30 may be made within the principle of the invention and the claims following.

What I claim is:—

1. An original container for salable units 35 adapted for use in connection with a dispensing mechanism, the said container being in the shape of a box in which the salable units are adapted to be packed in an orderly manner and having a bottom provided with an aperture through which an ejector device is adapted to pass in order to discharge said units.

2. An original container for salable units 45 adapted for use in connection with a dispensing mechanism, the said container being in the shape of a box in which the salable units are adapted to be packed in an orderly manner in a plurality of rows and having a bottom provided with apertures in line with said rows and through which ejector devices 50 are adapted to pass in order to discharge said units.

3. An original container for salable units 55 adapted for use in connection with a dispensing mechanism, the said container being in the shape of a box in which the salable units are adapted to be packed in an orderly manner and having a bottom provided with an aperture adjacent to each end through which an ejector device is adapted to pass in order 60 to discharge said units, said container adapted to be used in connection with said mechanism with either end contiguous thereto.

4. An original container for salable units 65 adapted for use in connection with a dispensing mechanism, the said container being

in the shape of a box in which the salable units are adapted to be packed in an orderly manner in a plurality of rows and having a bottom provided with apertures in line with said rows adjacent to each end and through 70 which ejector devices are adapted to pass in order to discharge said units, said container adapted to be used in connection with said mechanism with either end contiguous thereto.

5. An original container for salable units adapted for use in connection with a dispensing mechanism, the said container being in the shape of a box in which the salable units are adapted to be packed in an orderly 80 manner, said container having a removable cover and having a bottom provided with an aperture through which an ejector device is adapted to pass in order to discharge said units after removal of said cover.

85 In testimony whereof I have hereunto set my hand this 27th day of August, A. D. 1927.
